CLAIM

The ornamental design for a housing for an underwater vacuum cleaner, as shown and described.

DESCRIPTION

FIG. 1 is a top, front and right side perspective view of a housing for an underwater vacuum cleaner showing my new design;

FIG. 2 is a front elevational view thereof;

FIG. 3 is a top plan view thereof;

FIG. 4 is a left side elevational view thereof;

FIG. 5 is a bottom plan view thereof; and,

FIG. 6 is a rear elevational view thereof.

The cleaning unit and wheels shown in broken lines in FIGS. 1, 2, 4, 5 and 6 are for illustrative purposes only and form no part of the claimed design.

FIG. 1

FIG. 2

FIG. 3

FIG. 4

FIG. 5

FIG. 6
